TRAP OPERATING DEVICE FOR REFRIGERATOR CARS

Henry D. Doerman, Roseville, Calif.

Application September 25, 1944, Serial No. 555,739

7 Claims. (Cl. 182—8)

This invention is directed in general to an improvement in refrigerated railroad cars of the type wherein the refrigerating medium comprises ice retained in end bunkers at opposite ends of the car. In particular the invention is directed to, and it is an object to provide, a novel device adapted for manual operation, from a point exteriorly of the car, of the relatively inaccessible cap of the air trap which is conventionally incorporated in the water drainage outlet which leads downward from each bunker tank or pan.

For the purpose of opening the cap of the air trap to permit flushing of the bunker, removal of debris from the trap, or checking of the trap to assure that it is free and in working position, a workman must now enter the bunker to gain access to said cap, or must project a stiff wire or similar element up the drainage conduit from below the car; either procedure being inconvenient and requiring considerable expenditure of time.

I therefore provide a novel control mechanism operative from alongside the car to manually, quickly, and effectively open the cap of the air trap for each bunker and to selectively hold said cap open; the mechanism including a handle member whose relative position indicates visually to car-service men or train men whether or not each cap is in proper working position. If not it is only necessary to manipulate the above mentioned readily accessible handle.

A further object of the invention is to produce a simple and inexpensive device, and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a fragmentary sectional elevation showing my improved trap operating device in the position occupied by the parts thereof when the cap of the trap is closed.

Figure 2 is a similar view illustrating the position of the parts of the device when the cap is open.

Referring now more particularly to the characters of reference on the drawing, the numeral 1 indicates the bottom of the pan or tank of the ice bunker of a refrigerated railroad car; such car including a floor 2. Adjacent one wall 3 of the car the bottom of the pan 1 is provided with an upwardly opening bowl 4 which forms a sump

into which water from the melting ice in the bunker drains. The bottom of the bowl 4 is disposed at or adjacent the floor 2, and a water discharge or drainage conduit 5 extends vertically from within the bowl through the bottom thereof to a termination below the floor 2. The upper end of conduit 5 terminates intermediate the top and bottom of the bowl 4 and an air seal or trap is formed in said bowl by means of an inverted cup or cap 6, which normally engages over the upper end of conduit 5 with the lip 7 of said cap disposed some distance below the upper end of the conduit. Circumferentially spaced fingers 8 within the cap ride the upper end of the conduit 5 whereby to permit water to feed from the bowl under the lip 7, into the cap 6, over the upper end of the conduit 5, and thence downwardly therein. While water may thus drain from the bowl through the conduit 5, it will be evident that warm air cannot feed back into the ice bunker, with evident undesirable results.

For the purpose of permitting flushing of the ice bunker, cleaning of the trap, and similar operations, the cap 6 is hinged to one side of the bowl, as at 9, for swinging movement from the normal closed position shown in Fig. 1 to an open position above conduit 5, as shown in Fig. 2.

Water which spills through the conduit 5 is received by a trough 10 fixed in connection with and depending from the floor 2 below the car; said trough including a laterally projecting leg 11. The trough 10 is three-sided and is open on the side adjacent the car wall 3.

The above described air trap and the associated parts are conventional in refrigerated railroad car construction, and it is to this type of trap that I apply my invention.

My invention consists of the following structural arrangement:

40 A lever 12, disposed transversely of the car, extends from a point within the trough 10 outwardly to a termination below the adjacent longitudinal frame 13 of the car, the outer end portion of said lever 12 forming a handle 14. The handle 14 is disposed beneath the frame 13 so that it may not only be readily manually actuated but may also be easily seen by a person standing alongside the car.

Intermediate its ends the lever 12 is pivotally attached, as at 15, to a depending bracket 16 whereby said lever is mounted for rocking movement. The bracket 16 is fixed in connection with and depends from the floor 2 between the conduit 5 and the frame 13.

55 A rigid, substantially vertical link 17 is piv-

totally connected at its lower end, as at 18, to the inner end of the lever 12 within the trough 10. From the pivot 18 the link 17 extends upwardly into the conduit 5 and therein the upper end of said link is pivotally connected, as at 19, to a rigid ear 20 fixed on and depending into conduit 5 from the cap 6.

By reason of the above arrangement it will be seen that with downward movement of the handle 14 of lever 12 the inner end of the latter will move upwardly and impart corresponding movement to the link 17, which in turn will swing the pivotally mounted cap 6 from the closed position of Fig. 1 to the open position of Fig. 2.

For the purpose of holding the cap 6 open, as is necessary when the bunker pan or tank is being flushed, I provide a locking finger 21 which is pivotally mounted on the handle 14, as at 22, for swinging movement from a position substantially parallel to said handle, as shown in Fig. 1, to an upturned position, as shown in Fig. 2. The locking finger 21 is of such length that when in upturned position and engaged against the bottom of the adjacent car frame 13, the handle 14 will be maintained in a lowered position, and in which position the cap 6 is raised.

With my improved trap operating device for refrigerator cars, opening and closing of the cap of the trap is greatly facilitated; the cap can be selectively set in open position with ease; and a car service man or trainman can readily visually determine from a point alongside the car whether or not the trap is closed, and if not can close the same by a simple manipulation of the handle 14.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A trap operating device for a refrigerator car which includes an ice bunker air trap having an upstanding conduit extending from within the bunker to a point below the car floor exteriorally of the car, and laterally in from one side thereof, and a movable cap cooperating with said conduit at the top; said device comprising a transversely disposed lever extending beneath the car floor from a point below the conduit to a laterally outward point manually accessible from alongside the car, car connected means pivotally mounting said lever intermediate its ends for swinging movement in a vertical plane, and an upstanding link pivotally connected between the inner end of the lever and the cap, said link extending upwardly into the conduit for connection with the cap.

2. A device as in claim 1 including means arranged to selectively, and releasably, lock said handle in a cap opening position.

3. A trap operating device for a refrigerator car which includes an ice bunker air trap having an upstanding conduit extending from within the bunker to a point below the car floor exteriorally of the car, and laterally in from one side thereof, and a movable cap cooperating with said conduit

at the top; said device comprising a transversely disposed lever extending beneath the car floor from a point below the conduit to a laterally outward point manually accessible from alongside the car, car connected means pivotally mounting said lever intermediate its ends for swinging movement in a vertical plane, and an upstanding link pivotally connected between the inner end of the lever and the cap, said link extending upwardly into the conduit for connection with the cap; there being a selectively set, releasable locking device arranged to engage between the outer end portion of the lever and an adjacent portion of the car whereby to then maintain said lever in a cap opening position.

4. A device as in claim 3 in which said locking device comprises a rigid finger of predetermined length pivotally mounted on the lever for swinging movement between a position extending lengthwise of said lever to a position upstanding therefrom.

5. A trap operating device for a refrigerator car which includes an ice bunker air trap having an upstanding conduit extending from within the bunker to a point below the car floor exteriorally of the car, and laterally in from one side thereof, and a movable cap cooperating with said conduit at the top; said device comprising a transversely disposed lever extending beneath the car floor from a point below the conduit to a laterally outward point manually accessible from said one side of the car, a bracket depending from the car between the conduit and said one side of the car, the lever being pivoted intermediate its ends on said bracket for rocking movement in a vertical plane, the outer end portion of the lever forming a handle, a rigid upstanding link pivoted at its lower end to the inner end of the lever, the upper end portion of the link projecting into the conduit from below, and a pivotal connection between the upper end of the link and the interior of the cap.

6. A device as in claim 5 in which the handle forming portion of the lever is spaced below but adjacent a fixed part of the car; there being a locking finger pivoted on said handle forming portion of the lever for swinging movement from a lengthwise position to an upstanding position in end engagement with said car part, the lever being held in cap opening position when the finger is thus engaged.

7. A trap operating device for a refrigerator car which includes an ice bunker air trap having an upstanding conduit extending from within the bunker to a point below the car floor exteriorally of the car and laterally in from one side of such car, and a movable cap co-operating with said conduit at the top; said device including a lever pivoted intermediate its ends at a point underneath the car body, one free end of the lever projecting to a point in substantial alignment with the vertical axis of the conduit, a rigid substantially vertical link pivoted to such end of the lever and projected through the conduit and being connected at its other end with the cap, the other free end of the lever projecting to a point immediately adjacent the vertical plane of the side wall of the car and readily accessible from a point in a plane outside such plane of the side wall of the car, whereby such lever may be grasped by an operator standing beside the car and rocked on its pivot to cause the link to move the cap.

HENRY D. DOERMAN.
